UNITED STATES PATENT OFFICE.

JOSEF REULEAUX, OF WILKINSBURG, PENNSYLVANIA, ASSIGNOR TO
ALEXANDER LAUGHLIN, OF SEWICKLEY, PENNSYLVANIA.

CONTINUOUS HEATING-FURNACE.

SPECIFICATION forming part of Letters Patent No. 782,697, dated February 14, 1905.

Application filed September 21, 1904. Serial No. 225,393.

To all whom it may concern:

Be it known that I, JOSEF REULEAUX, of Wilkinsburg, in the county of Allegheny and State of Pennsylvania, have invented certain new and useful Improvements in Continuous Heating-Furnaces; and I do hereby declare the following to be a full, clear, and exact description of the invention, such as will enable others skilled in the art to which it appertains to make and use the same.

As is well known in the art, prior to the invention covered by Letters Patent of the United States No. 588,702, issued to Alexander Laughlin and myself August 24, 1897, considerable difficulty was experienced in the heating of billets in continuous furnaces because of the billets being cooled at those points in contact with the water-cooled pipes or tubes constituting the bearings for the billets in their passage through the furnace. This defect was remedied according to said invention by passing the billets onto hearths, where they were allowed to remain for a short time before being removed or discharged from the furnace, the heat of the hearth serving to cause the black or chilled spots to disappear and the hearth itself being protected as against excessive heating and consequent softening.

The primary object of the present invention is to allow the hot gases to come in direct contact with the cooled portions of the billets while on the hearth.

It is a further object of the present invention to maintain the integrity of the bearings from one end of the furnace to the other, said bearings extending through and beyond the hearth and constituting the means for effecting the automatic discharge of the billets after the manner contemplated by the invention patented to the said Laughlin and myself by re-issued Letters Patent No. 11,666, dated May 31, 1898.

Further objects are to insure the thorough heating of the hearth and billets and to enable worn portions of the hearth to be readily removed and replaced.

The invention will be hereinafter fully set

forth, and particularly pointed out in the claims.

In the accompanying drawings, Figure 1 is 50 a vertical longitudinal sectional view of a furnace constructed in accordance with my invention. Fig. 2 is a horizontal sectional view on line 2 2, Fig. 1. Fig. 3 is a transverse section on line 3 3, Fig. 1. Fig. 4 is a sectional 55 view of a slight modification.

The form of furnace shown in the drawings is constructed after the manner comprehended by the above-noted patents, 1 designating the bed of the furnace, having raised longitudinal 60 supports 2 and a transverse pier 3 for the bearings 4 for the billets, such bearings being extended longitudinally of the combustion-chamber from the charging-opening 5 to the discharge-opening 6, the arrangement of the 65 bearings being such as to provide for the automatic discharge of the billets from the point of highest heat in accordance with the invention covered by said reissued Letters Patent No. 11,666. These bearings are composed of 70 hollow tubes or pipes through which water may circulate from end to end, and the pipes are carried downwardly on an incline over the point of highest heat—that is to say, over the gas-inlet port 7. 75

8 designates a hearth extending transversely of the furnace, intersecting and itself intersected by the bearings 4 and over which the billets are designed to travel as a line thereof is pushed through the furnace by the pushing 80 mechanism, (indicated at 9.) The bearings in their passage through the hearth occupy such relation to the top surface thereof as to insure the automatic removal of the billets from the bearings as they are pushed over the hearth, 85 spaces being left within the hearth to permit the hot gases to contact directly with the cool portions of the billets, and thus effectively remove spots and secure uniformity in the heating of the billets at every point. The bearings themselves are shown as being bent 90 slightly downwardly from the side of the hearth at which they enter onto the other side thereof, from whence they are inclined, as

above stated, so that as the billets leave the hearth they are automatically discharged from the furnace. The bearings being continuous from one end of the furnace to the other, even where intersected by the hearth, water may be introduced into one end of each bearing-pipe and flow out at the other. If desired, the billets may be withdrawn from the hearth through the openings 12 in the sides of the furnace.

The hearth is composed of a series of separate removable slabs or sections of metal or refractory material. It is between adjacent slabs that the bearings 4 are passed, the spaces therefor forming pockets for the bearings and openings for the admission of the gases against the under sides of the billets. These slabs are mounted on a metallic base 13, with which they are interlocked as against displacement by the billets in their passage thereover. In Fig. 1 I have shown the hearth-slabs as having sockets in their under sides to accommodate a spline 14, extended longitudinally of the base, while in Fig. 4 I have shown each slab as having at the receiving side of the hearth a depending spline or tongue 15 for engaging a shouldered cut-out in the base. By either means the slabs are held in place, since the strain of the billets thereon is transverse to the interlocking with the base. Furthermore, in the event of injury to any portion of the hearth it is only necessary to remove one or more slabs without disturbing the others instead, as heretofore, of having to provide an entirely new hearth. The base 13 is cooled by water circulating through pipes 16.

The hearth is shown as located on a bridge wall or pier 17, formed with one or more transverse openings 18 to permit of the passage of the gases beneath as well as above the hearth, a continuous flow of gases being maintained beneath the line of billets clear to the discharge-flue 19, leading to the stack. Intermediate pier 17 and the gas-inlet port 7 is a cinder-pocket 20.

The advantages of my present invention are manifest to those skilled in the art. Although I have shown the bearings as passing through the hearth on lines angular to the top flat surface of the latter, yet it is manifest that the same results may be obtained by passing the bearings through the hearth on straight horizontal lines and having the upper surface of the hearth inclined from the discharging side thereof toward the receiving side. (See Fig. 4.) In each instance I secure clear openings for the gases within the hearth beneath those portions of the billets previously in contact with the water-cooled bearings.

The improvements herein described are readily applicable to forms or constructions of heating-furnaces other than those shown. Likewise it is not my intention to limit the

invention to any particular construction of the hearth.

65

I claim as my invention—

1. A furnace having in combination therewith, bearings arranged longitudinally thereof, a hearth intersecting said bearings and onto which the billets are received from the 7c bearings, said hearth having spaces therein in line with the bearings for the admission of the gases against the under sides of the billets on the hearth, and means for pushing the billets over the bearings and hearth.

75

2. A furnace having in combination therewith, bearings arranged longitudinally from end to end thereof, a hearth intersecting said bearings and over which the billets are designed to pass, means for disengaging the billets from the bearings as they travel over the hearth, means for permitting the gases, while the billets are on the hearth, to engage those portions of the billets previously in contact with the bearings, and means for pushing the 85 billets over the bearings and hearth.

3. A furnace having in combination therewith, bearings arranged longitudinally thereof, a hearth intersected by said bearings at an angle to the top surface thereof, said hearth 90 having open-top spaces for the bearings, and means for pushing the billets over the bearings and hearth, the relative angularity of the intersecting portions of the bearings to the top surface of the hearth serving to cause the 95 billets to be removed from the bearings as they travel over the hearth.

4. A furnace having in combination therewith, bearings arranged longitudinally thereof, a hearth intersected by said bearings and having spaces through which said bearings are passed at an angle to the top of the hearth, and means for pushing the billets over the bearings and hearth.

100

5. A furnace having in combination therewith, bearings arranged longitudinally thereof, a flat top hearth intersected by said bearings and having spaces through which said bearings are extended on an incline from the receiving to the discharge side of the hearth, 110 and means for pushing the billets over the bearings and hearth.

105

6. A furnace having in combination therewith, bearings arranged longitudinally thereof, a hearth intersecting said bearings and onto which the billets are received from the bearings, said hearth being composed of a base, a series of removable slabs and means for interlocking said slabs and base to prevent the former from being displaced by the billets, 115 open-top spaces being formed between some of said slabs to accommodate said bearings and admit gases against the under sides of the billets on the hearth, and means for pushing the billets over the bearings and hearth.

120

7. A furnace having in combination there-

125

with, bearings arranged longitudinally thereof, a gas-inlet at one end, a hearth intersecting said bearings, and a support for said hearth having passages for the gases beneath the hearth, said support being located adjacent to the gas-inlet.

8. A furnace having in combination therewith, bearings arranged longitudinally thereof, a gas-inlet at one end, a hearth intersecting said bearings, and a bridge-wall support-

ing said hearth having a transverse opening or openings therein beneath the hearth forming passages for the gases.

In testimony whereof I have signed this specification in the presence of two subscribing witnesses.
